UNITED STATES PATENT OFFICE

ARTHUR F. PYM, OF SWAMPSCOTT, MASSACHUSETTS, ASSIGNOR TO UNITED SHOE MANUFACTURING CORPORATION, OF PATERSON, NEW JERSEY, A CORPORATION OF NEW JERSEY

INSOLE-POSITIONING MEANS

Application filed January 11, 1928, Serial No. 245,954. Renewed February 12, 1929.

This invention relates to means for positioning insoles on their lasts during a portion of the operations of shoe manufacture. An object of the invention is to provide improved insole-positioning means which will be simple and inexpensive and which will effectively position an insole in proper relation to a last without interfering with operations to be performed upon the shoe materials or with machines for performing those operations, and of such a character as to adapt it to be readily applied to the insole and last and removed therefrom.

To this and other ends, the invention provides a novel insole-positioning device of a type which is portable with the last and insole, comprising, in its illustrated form, a sheet metal clamping member adapted to be applied over the bottom face of the insole transversely of the forepart of the last and having thereon a pair of pins arranged to project through holes in the insole into corresponding holes in the bottom of the last in locations spaced widthwise of the forepart to attach the device to the last and to position the insole accurately in proper lengthwise, lateral and angular relation to the last. The device herein shown is thus adapted for use where the proper relation between the insole and the last is predetermined by the use of holes formed in the last and in the insole at the forepart in such locations as to align with one another when the insole is in proper position, in accordance with a method disclosed in Letters Patent No. 1,674,060, granted upon my application on June 19, 1928. Preferably, in order to retain the device in operative position, the clamping member is formed of spring metal so shaped as to adapt it to be sprung into clamping position in applying the device to the last and insole, and the pins are so arranged that by the resiliency of this member in its clamping position they are cramped in the holes in the last.

The invention will now be more particularly described by reference to the accompanying drawings and thereafter pointed out in the claims.

In the drawings,

Fig. 1 is a perspective view of a last with

an insole positioned thereon by the use of means constructed in accordance with the present invention;

Fig. 2 is a section on the line II—II of Fig. 1;

Fig. 3 is a view showing the insole-positioning device detached; and

Fig. 4 is a view showing said device in cross-section.

The drawings show a last *a* and an insole *b* each of which is provided in the bottom of its forepart with three holes adapted for use not only to determine the proper position of the insole in relation to the last, but also in positioning the last and its shoe materials in proper relation to a toe-lasting or other machine in further accordance with the method disclosed in the Letters Patent above mentioned. One of the holes in the insole, as shown at 10 in Fig. 1, is located near the toe end of the insole and in position to align with a corresponding hole (not shown) in the bottom of the last, while the other two holes in the insole, indicated at 12 in Fig. 2, are spaced apart widthwise of the last at the rear of the hole 10 in position to align with corresponding holes 14 formed in metal bushings 16 in the bottom of the last. The device herein shown for positioning the insole on the last is so formed as to utilize the rear pairs of holes 12 and 14 in the insole and in the last, and to that end comprises a clamping member 18 of such dimensions as to adapt it to extend lengthwise in transverse or widthwise relation to the forepart of the insole, the device being provided on one side thereof near its opposite ends with pins 20 which, in the construction illustrated, are secured to the member 18 by riveting them to this member and are so arranged as to adapt them to project through the holes 12 in the insole into the holes 14 in the last. The clamping member 18 is formed preferably of sheet metal, such as steel, which is resilient and of such contour that the member presents initially a concave face toward the bottom face of the insole and is adapted to be sprung into a position in which it lies throughout its length in substantially contiguous relation to said face. In the construction shown the clamping member

100

is of greater length than width, its length being such as to adapt it to extend over a large portion of the width of the insole with the pins 20 spaced far enough apart for effective action in holding the insole in proper angular relation to the last, while its width is limited as far as is consistent with proper strength of the member in order to facilitate the springing of the member into clamping position. All that is necessary in applying the device to the work is to present it with the pins 20 substantially in position to enter the holes in the insole and the last, and then to press the device down to force the pins into the holes and to spring the member 18 into a position close to the bottom face of the insole, the springing of the member serving to bring the pins into substantially parallel relation to the holes so that they will enter the holes readily. It will be evident that the member 18 will then act by its resiliency to cramp the pins 20 in the holes 14 in the last, so that the device will be held securely in place. When it is desired to remove the device, this may be conveniently done by inserting a suitable tool between the insole and the member 18 and prying the latter up until the pins 20 are withdrawn from the holes. To facilitate such detachment of the device, the member 18 is preferably formed with edges that are beveled on the side toward the insole, as indicated at 22 in Fig. 4.

It will be understood that the insole-positioning device above described is applied to the work when the insole is assembled with the last, and in its illustrated use it is intended to remain in operative position during the pulling-over and side-lasting operations on the shoe, after which it will be removed to permit the holes in the insole and last to be used in positioning the shoe for the toe-lasting operation in the manner disclosed in the Letters Patent mentioned. Since the clamping member 18 is formed of thin sheet metal which lies close to the bottom face of the insole, and since there is nothing on the outer side or face of this member which projects to any substantial extent heightwise of the last, it will be evident that the device is of such construction as not to interfere with the presentation of the shoe to a pulling-over machine of the usual type. There is likewise nothing in the construction of the device and its relation to the shoe to interfere with the operation of the side-lasting machine, since in addition to the above-mentioned characteristics the device is located at a wide portion of the insole, as distinguished from the comparatively narrow shank, and terminates far enough from the side edges of the insole to allow ample room for the overlaying and fastening of the upper.

In addition to the advantages above mentioned, it is to be noted that the device described positions the insole in proper length-

wise, lateral and angular relation to the last, that it is of simple construction and inexpensive to manufacture, and that the same device may be used interchangeably in making shoes of a number of different sizes. Furthermore, the arrangement whereby the clamping member extends widthwise of the forepart to locations near the side edges of the insole contributes effectively to the holding of the side portions of the insole close to the bottom face of the last. 70 75

The drawings illustrate an insole which has been previously molded to conform substantially to the contour of the bottom of the last, but it will be understood that the invention does not depend for utility upon the use of a molded insole. As shown, moreover, in Fig. 1, the heel end portion of the insole is fastened to the last by the use of a tack *t* to hold it from shifting laterally after the insole as a whole has been positioned by the use of the device hereinbefore described. While the use of such a tack may be desirable in operating upon some kinds of work, it will be recognized that frequently conditions will be such that it may be dispensed with. It is further to be understood that the invention, in its more general aspects, is not limited to insole-positioning means provided with two pins to enter holes in the insole and last, nor to an arrangement of the pins and holes in the particular relation to the last herein disclosed. Moreover, it will be recognized that the utility of the invention is not dependent upon the use of a device having pins or projections of the particular form and construction herein illustrated, and in the appended claims the term "pins" is accordingly used in a general rather than a restrictive sense to define those portions of the device that enter the holes in the insole and last. 90 95 100 105

Having described the invention, what I claim as new and desire to secure by Letters Patent of the United States is:—

1. Means for positioning an insole on a last comprising a member adapted to be applied over the bottom face of the insole and portable with the last and insole, said member having on one side thereof a plurality of pins arranged to project through the insole into holes in the bottom of the last to position the insole in proper lengthwise, lateral and angular relation to the last, the opposite side of said member being free from any substantial projection heightwise of the last. 110 115 120

2. Means for positioning an insole on a last comprising a sheet metal clamping member adapted to be applied over the bottom face of the forepart only of the insole and to lie throughout its length in substantially contiguous relation to said face, said member being portable with the last and insole and having thereon at one side only a plurality of pins, said pins being arranged to project through the insole into holes in the bottom 130

of the last to position the insole in proper lengthwise, lateral and angular relation to the last.

3. Means for positioning an insole on a last comprising a resilient clamping member formed to present initially a concave face toward the bottom face of the insole and adapted to be sprung into clamping position, said member comprising a strip of metal of greater length than width having thereon at its opposite ends pins arranged to project through the insole into holes in the bottom of the last and to be cramped in said holes by the resiliency of said member.

4. Means for positioning an insole on a last comprising a clamping member portable with the last and insole and of such dimensions as to adapt it to be applied to the bottom of the forepart of the insole without extending rearwardly of the forepart, said member having thereon at one side only a plurality of pins, said pins being arranged to project through the insole into holes in the bottom of the forepart of the last which are spaced apart widthwise of the last.

5. Means for positioning an insole on a last comprising a clamping member of greater length than width portable with the last and insole and so formed as to adapt it to be positioned lengthwise in transverse relation to the bottom of the forepart of the insole for holding the opposite side portions of the insole close to the last, said member having at each end thereof a pin arranged to project through the insole into a hole in the bottom of the last.

6. Means for positioning an insole on a last comprising a resilient sheet metal clamping member of greater length than width and of such dimensions as to adapt it to be positioned lengthwise in transverse relation to the bottom of the forepart of the insole, said member having at each end thereof a pin arranged to project through the insole into a hole in the bottom of the last and being so formed as to act by its resiliency to cramp the pins in the holes in the last.

7. Means for positioning an insole on a last comprising a clamping member adapted to be applied over the bottom face of the insole in substantially contiguous relation to said face and having thereon means arranged to project through the insole into the bottom of the last to hold the member in place, said member being beveled at its edge on the side toward the insole to facilitate its removal from the last and insole.

8. In insole-positioning means, the combination with a last having in its bottom portion a plurality of holes arranged in predetermined relation to the edge of the last bottom and adapted to align with holes formed in an insole in similar relation to the edge of the insole, of a device portable with the last and insole and having on one side thereof

a plurality of pins arranged to project through the holes in the insole into the holes in the last to position the insole in proper lengthwise, lateral and angular relation to the last, the opposite side of said device being free from any substantial projection heightwise of the last.

9. In insole-positioning means, the combination with a last having a plurality of holes in the bottom of its forepart, of a member portable with the last and adapted to be applied over the bottom of the forepart of an insole on the last in clamping engagement with the insole, said member having thereon at one side only a plurality of pins, said pins being arranged to project through holes in the insole into the holes in the last.

10. In insole-positioning means, the combination with a last having in the bottom of its forepart a plurality of holes spaced apart widthwise of the last, of a resilient sheet metal member of greater length than width so formed as to adapt it to extend lengthwise in transverse relation to the bottom of the forepart of the last in clamping engagement with an insole on the last and having thereon a plurality of pins arranged to project through the insole into the holes in the last and to be cramped in said holes by the resiliency of said member.

In testimony whereof I have signed my name to this specification.
